UNITED STATES PATENT OFFICE.

BERNARD T. McGLONE, OF CHICAGO, ILLINOIS, AND GEORGE ROSS,
OF HAMMOND, INDIANA.

CASTING-MACHINE.

No. 844,460.

Specification of Letters Patent.

Patented Feb. 19, 1907.

Application filed February 12, 1906. Serial No. 300,622.

To all whom it may concern:

Be it known that we, BERNARD T. McGLONE, and GEORGE ROSS, citizens of the United States, residing at Chicago, Illinois, and Hammond, Indiana, respectively, have invented certain new and useful Improvements in Casting-Machines, of which the following is a specification.

Our invention relates to casting-machines, and more particularly to machines for producing bushings and similar articles; and its objects are to provide an apparatus of a simple and durable construction which can be operated at a comparatively high speed, to provide an apparatus in which the finished article can be readily removed from the mold, to provide an apparatus which will permit of the use of a sectional matrix, whereby easy removability of the casting is attained, and to provide a machine in which the ejector constitutes one side of the mold. These objects and other advantages, which will hereinafter appear, we attain by means of the construction illustrated in preferred form in the accompanying drawings, wherein—

Figure 1 is a view partly in section and partly in elevation, of our improved apparatus with the parts in position for casting. Fig. 2 is a view similar to Fig. 1 of the upper part of the device with the mold-bottom in its raised position, the matrix removed, and a completed casting resting upon the bottom just as it comes from the matrix; and Fig. 3 is a cross-section taken on the line 3 of Fig. 1.

In the accompanying drawings the object illustrated as cast is a bushing, and this is what the device is primarily intended to produce; but it is apparent that the invention may be applied to the production of many other articles and is not limited to bushings. The device consists of a flask or casing 4, supported upon a base 5 of any suitable construction and to which it is secured. A matrix 6 is slidably mounted within the casing and rests upon a reciprocable bottom 7, operated by means of a rack 8, upon which it rests, mounted upon the base 5 in a manner to be presently described.

The body portion of the rack 8 is hollow and is supported upon a vertical guide 10, secured to the base 5 axially in line with and below the casing 4. The rack 8 slides freely

upon the guide 10 and is operated by means of a pinion 9, mounted upon a shaft 11, journaled in bearings formed in one of the side pieces of the base 5.

When it is desired to form a hollow article, a core-piece 12 is secured to the upper end of the guide 10 and extends through the bottom 7 and matrix 6 into the cap 13, which rests upon the top of the flask or casing 4. The core 12 also serves to act as a guide for the movable bottom 7, which slides freely thereon and serves to keep the same in alignment when it is being raised by means of the rack 8 and pinion 9.

In order to permit of the ready removal of the article cast from the matrix when the latter has been elevated above the casing in the position shown in Fig. 2, the matrix may be made in two parts, as shown in Figs. 1 and 3, and molten metal is introduced into the matrix through the pouring-gate 14, formed in the periphery of the same adjacent to the casing 4, and through the cap 13. The pouring-gate 14 is preferably located at the point on the periphery of the matrix where the two sections come together, as illustrated in Fig. 3.

From the foregoing it will be seen that in an apparatus constructed in accordance with our invention a great number of castings can be made in a comparatively short time, as the article can be removed from the mold as soon as it has set and the mold again made ready by the raising and lowering of the bottom portion 7 without in any way disturbing the main flask or removing it from position. Furthermore, such an apparatus will permit of the use of a matrix adapted for continuous operations in the place of one which would be destroyed at each casting operation. It will further be apparent that by the use of a matrix slideable in the casing there will not be the resistance to sliding motion in removing the casting that there would be were the casting alone to be pushed out, as the heated metal would take a much firmer hold upon the side of the casing than the matrix does.

Other advantages of the device will readily occur to those familiar with the art.

Having thus described our invention and illustrated its use, what we claim as new, and desire to secure by Letters Patent, is the following:

1. In combination in a casting-machine, an inner sectional casing, an outer casing entirely surrounding and covering the joints of the inner casing, and means whereby the inner casing may be slid through the outer casing. 40
2. In combination in a casting-machine, an outer casing, an inner sectional casing sliding therethrough and disconnected therefrom, and means whereby the inner casing may be slid through the outer casing. 45
3. In combination in a casting-machine, an outer casing, an independent inner casing divided longitudinally into sections and slideable through the outer casing and covered at its joints thereby and an ejector adapted to slide the sectional inner casing through the outer casing. 50
4. In combination in a casting-machine, an outer casing, an independent inner casing divided longitudinally into sections and slideable through the outer casing and covered at its joints thereby and a movable mold-section adapted to slide through the outer casing and force out the molded article and inner casing. 55
5. In combination in a casting-machine, an outer casing, an independent inner casing divided longitudinally into sections and provided with recesses, slideable through the outer casing and covered at its joints thereby and an ejector adapted to slide the sectional inner casing through the outer casing. 60
6. In combination in a casting-machine, an outer casing, an independent inner casing divided longitudinally into sections and provided with recesses, slideable through the outer casing and covered at its joints thereby and a movable mold-section adapted to slide 65
- 35 through the outer casing and force out the molded article and inner casing. 70
7. In combination in a casting-machine, a vertical outer casing, an independent inner casing divided longitudinally into sections and slideable therethrough and a reciprocable bottom mold-section adapted to force out the inner casing. 75
8. In combination in a casting-machine, a vertical outer casing, an independent inner casing divided longitudinally into sections and provided with recesses, slideable through the outer casing and covered at its joints thereby and a reciprocable bottom mold-section adapted to force out the inner casing. 80
9. In combination in a casting-machine, a vertical outer casing, a guide-core, an independent inner casing divided longitudinally into sections and slideable through the outer casing and covered at its joints thereby, a bottom section reciprocable through the outer casing and adapted to force out the inner casing and the molded article. 85
10. In combination in a casting-machine, a vertical outer casing, and a removable independent inner casing divided longitudinally into sections and adapted to form a matrix, provided with a pouring-gate on the periphery at the juncture of the parts of the sectional casing. 90

In testimony whereof we have hereunto signed our names in the presence of the two 7c
subscribed witnesses.

BERNARD T. McGLONE.
GEO. ROSS.
